UNITED STATES PATENT OFFICE.

FREDERICK W. DRESSEL, OF NEW YORK, N. Y.

DESIGN FOR A LAMP-CHIMNEY.

41,786.

Specification for Design.

Patented Sept. 19, 1911.

Application filed April 28, 1908. Serial No. 429,788. Term of patent 7 years.

To all whom it may concern:

Be it known that I, FREDERICK W. DRESSEL, a citizen of the United States, residing at the city of New York, borough of Manhattan, in the county and State of New York, have invented a new, original, and ornamental Design for a Lamp-Chimney, of which the following is a specification, reference being had to the accompanying drawing forming part thereof, and in which—

Figure 1 is a side view showing a lamp chimney incorporating my said design, and drawing, forming part thereof.

In said drawings the lamp chimney is shown comprising essentially an outwardly

curved body portion diminishing in diameter toward its opposite ends where the same merge with relatively narrow cylindrical portions forming flat bands terminating in rounded beads or rims, which beads or rims project laterally beyond the sides of said cylindrical portions or bands.

I claim:

The ornamental design for a lamp chimney as shown, and described.

FREDERICK W. DRESSEL.
